INVENTOR
BENJAMIN L. MOSS,

BY *Benjamin L. Moss*
ATTORNEYS.

UNITED STATES PATENT OFFICE.

BENJAMIN L. MOSS, OF DETROIT, MICHIGAN.

FUSE.

1,391,399.

Specification of Letters Patent. Patented Sept. 20, 1921.

Application filed March 22, 1920. Serial No. 367,921.

To all whom it may concern:

Be it known that I, BENJAMIN L. Moss, a citizen of the United States of America, residing at Detroit, in the county of Wayne, 5 and State of Michigan, have invented certain new and useful Improvements in Fuses, of which the following is a specification, reference being had therein to the accompanying drawings.

This invention relates to fuses, and has special reference to that type of fuse commonly known as a cartridge fuse adapted to be detachably mounted in sockets, clips or other holding devices to connect such devices 10 and establish an electric circuit.

The primary object of my invention is to provide a cartridge fuse in which one and only one, fuse or conductor can be mounted, thus preventing the use of additional fuses 20 or conductors to increase the current carrying capacity of the cartridge fuse. By preventing overloading of the fuse the same serves the purposes for which it was intended and meets one of the requirements of 25 the Underwriters' Association.

Another object of this invention is to provide a fuse having separable parts, one of which constitutes a fuse holder and the other of which constitutes an inclosure for the fuse 30 holder. Both parts are constructively arranged so that the fuse may be safely handled, especially when being mounted or dismounted relative to the devices to be connected to the fuse.

A further object of my invention is to provide a fuse holder in which a fuse may be easily and quickly mounted, the fuse proper being braced so that it cannot be accidentally broken or become accidentally dis- 35 placed during handling of the fuse.

A still further object of my invention is to accomplish the above results by a durable and inexpensive construction that will be hereinafter considered and then claimed, and 40 reference will now be had to the drawing, wherein—

Figure 1 is a side elevation of the fuse;

Fig. 2 is a similar view showing a cartridge in longitudinal section;

Fig. 3 is a cross sectional view of the fuse;

Fig. 4 is a plan of a portion of the fuse holder with the fuse therein;

Fig. 5 is a perspective view of a detached fuse;

Fig. 6 is a plan of a portion of the fuse 55 holder with the fuse removed, and

Fig. 7 is an end view of the same.

In the drawing, the reference numeral 1 denotes a finger piece or insulator that may be made of hard rubber, fiber or other insulation material, and said insulator is preferably rectangular in plan with one of its faces provided with an integral fuse holder 2, said holder being in the form of a rib or flange of less length and width than the insulator. In the outer edge or face of the holder there is a longitudinal groove 3 providing a three walled seat for a fuse 4 which is preferably in the form of a ribbon placed on its edge within the groove 3, so that the 70 side walls of the ribbon are braced by the side walls of the groove, and in practice the ribbon is bowed or curved in a vertical plane so that its central portion will protrude from the groove, as best shown in Fig. 2, thus 75 permitting of the fuse melting when an excessive current of electricity attempts to pass therethrough. In other words, the walls of the groove do not retard the action of the fuse, but do preclude the mounting of more 80 than one fuse in the groove, consequently the current carrying capacity of the cartridge fuse, as a whole, cannot be materially increased. The fuse receiving groove of the holder is an important feature of my invention 85 as it prevents overloading of the fuse.

The fuse 4, which is made of soft solder or any material having a limited current carrying capacity, has its ends provided with angle pieces 5 to which the ends of the fuse 90 are soldered or otherwise connected, as at 6, and said angle pieces afford stops and finger pieces 7.

In order that the holder 2 may accommodate the angle pieces 5, said holder, at the 95 ends of the groove 3, has sockets 20 of greater depth than the groove and set to one side thereof, as best shown in Figs. 6 and 7, and it is into these sockets that the ends of the angle pieces 5 extend and coöperate with 100 the groove in correctly positioning the fuse 4. The finger pieces or stops 7 overlie the face of the holder 2 and the finger nails can be placed under the finger pieces or stops to

extract the fuse or severed parts thereof when it is desired to remove the fuse or substitute a whole fuse for a severed one. The finger pieces or stops 7 also limit the seating of the fuse in the holder.

The reference numeral 8 denotes a cartridge made of hard rubber, fiber or other insulation material, and said cartridge is provided with a longitudinal recess 9 throughout the length thereof and with opposed facets 10. Mounted on reduced ends of the cartridge 8 are metallic caps 11 which may be fixed thereon by pins 12 or other fastening means, and each cap has its end wall provided with exhaust openings 13 and a concentric screw opening 14. The openings 13 communicate with the recess 9 and in the openings 14 are mounted screws 15 for holding resilient yieldable contact members 16. These contact members have the screw held ends thereof extending between the end walls of the caps and the ends of the cartridge 8, so that the outer ends of the contact members will be clamped and held in addition to the screws 15.

The contact members 16 extend inwardly and protrude beyond the inner ends of the caps, within the recess 9, so that the inner ends of the contact members will be exposed when viewing the open recess. The contact members 16, screws 15 and caps 11 constitute terminals for the cartridge.

The recess 9 is adapted to receive the holder 2 which enters the recess somewhat as a tongue entering a groove, and the end walls of the holder are cut away or notched, as at 17, so as to expose the end edges of the angle pieces 5, and it is against these angle pieces that the resilient contact members 16 frictionally press, as best shown in Fig. 2, thus providing a metal to metal connection. The resiliency of the contact members 16 not only causes the fuse holder 2 to be retained within the cartridge 8, but establishes a positive engagement with the angle pieces 5 so that there will be a metallic conductor from one cap to the other, thus permitting of a circuit being established when the capped ends of the cartridge are placed in sockets, clips or other devices representing the terminals of an electrical circuit. Since the finger piece or insulator 1 is of less length than the cartridge and has its side edges practically in the same plane as the facets 10 of the cartridge, the finger piece or insulator 1 will facilitate installation of the cartridge, without any danger of the fingers contacting with the caps 11 and possibly establishing a connection between the caps independent of the fuse, which might cause the person installing the fuse to be shocked. The finger piece or insulator 1 is an appraisable feature of my invention and contributes to safe handling of the fuse.

In operation, the cap openings 13 insure ventilation of the recess 9, consequently when the fuse 4 is burned out there cannot be an excessive compression of gases or air within the recess 9 and if the cartridge 8 is completely dislodged or the holder 2 blown therefrom, as would be the case when the cartridge is held, the separation of the two parts of the fuse cannot be very forcible.

By reference to Fig. 2, it will be observed that the resilient contact members 16 are compound curved so that the intermediate portions thereof may be engaged by the inner ends of the screws 15, and with said screws of sufficient length and in threaded engagement with the caps 11, the screws may be adjusted to shift the inner ends of the contact members 16, so as to increase or decrease the pressure of said contact members against the angle pieces 5. It is therefore possible to adjust the screws 15 and cause the contact members to hold the removable fuse with a desired degree of yieldability, especially to permit of the removable fuse being withdrawn from the cartridge without disturbing the cartridge relative to its holding means.

In addition to the resilient contact members 16 serving as a yieldable connecting means between the cartridge and fuse holder, I may use resilient clasps 18 mounted on the insulator 1, at the sides of the holder 2 and adapted to engage the facets 10 of the cartridge 8, the cartridge being snapped into position on the holder 2 and between the clasps. These clasps are of a conventional form and may represent any suitable hold-fast device for temporarily retaining the cartridge on the fuse holder.

It is thought that the operation and utility of the cartridge fuse will be apparent without further description, and while in the drawing there is illustrated a preferred embodiment of my invention, it is to be understood that the structural elements are susceptible to such changes, in size, shape and manner of assemblage as fall within the scope of the appended claims.

What I claim is:—

1. In a cartridge fuse, a holder having a three walled groove, and a bowed fuse in said holder groove and protruding therefrom.
2. A cartridge fuse as characterized in claim 1, wherein angle pieces on the ends of the fuse are seated in said holder and provide exposed contact surfaces adapted to be included in an electric circuit.
3. A cartridge, a fuse holder therein and removable from the side of said cartridge, and means carried by said fuse holder engaging the outer side of said cartridge adapted to retain it in said cartridge.
4. In a cartridge, resilient contact members in the ends of said cartridge, a fuse,

and a fuse holder for said fuse held between said contact members and removable from a side of said cartridge.

5. A cartridge as characterized in claim 4, wherein angle pieces on the ends of said fuse establish an electrical connection between said fuse and said contact members and afford finger engaging means for removing the fuse.

6. A cartridge having an open side recess therein, caps on the ends of said cartridge, said caps having portions partly closing the side recess of said cartridge, and fuse carrying means insertible in the side recess of said cartridge between the portions of said caps and establishing an electrical connection from one end of said cartridge to the other.

7. A cartridge as characterized in claim 6, wherein said means closes said recess and protrudes from said cartridge to overlie said caps and facilitate removal from the cartridge recess.

8. A cartridge adapted to be held sta-

tionary and having a groove therein, a fuse 25 in said cartridge adapted to be burned out, and means snugly fitting in the cartridge groove supporting said fuse within said cartridge and adapted to be bodily blown outward from a side of said cartridge.

9. In a cartridge, a fuse, angle pieces holding said fuse in an operative position and affording finger engaging means for removing said fuse or destroyed parts thereof, and adjustable contact members engaging 35 said angle pieces and establishing a connection therewith for electrical purposes.

10. A cartridge as characterized in claim 9, wherein adjustable means permit of the resiliency of the contact members being increased or decreased.

In testimony whereof I affix my signature in the presence of two witnesses.

BENJAMIN L. MOSS.
